AUTOMATIC INTERLOCKING SYSTEM

Earl M. Allen, Swissvale, Pa., assignor to The Union Switch & Signal Company, Swissvale, Pa., a corporation of Pennsylvania

Application January 23, 1932, Serial No. 588,275

5 Claims. (Cl. 246—114)

My invention relates to apparatus for automatic interlocking systems for governing traffic at grade crossings, and particularly to automatic interlocking systems governing traffic at a grade crossing of two railways. A feature of my invention lies in the provision of simple and reliable apparatus for governing the traffic of two railways that cross at grade at the intersection of two highways by the same signals that are normally used to govern the usual highway traffic; the apparatus being so arranged that preference is given to the traffic on the railways over that on the highways. It will be understood, however, I do not wish to confine myself to railways crossing at grade at a highway intersection, but my invention is equally adapted to other grade crossings used by two different classes of traffic, one of which is to be given preference over the other at the intersection. Other features of my invention will appear as the specification progresses.

I will describe one form of apparatus embodying my invention, and will then point out the novel features thereof in claims.

The accompanying drawing is a diagrammatic view of one form of apparatus embodying my invention applied to a grade crossing at which two railways cross at grade at the intersection of two highways or streets. The highway traffic is normally governed at the intersection by the usual traffic light signals, which signals also serve to govern all railway traffic over the grade crossing.

Referring to the drawing, a city street A is traversed by a railway C, and a city street B is occupied by a street railway D, the two railways crossing each other at grade at the street intersection. Each railway is a single track line on which traffic normally moves in either direction. While my invention is equally well adapted to all railways irrespective as to what propulsion power they may use, I shall refer to railway C as a high speed interurban line and railway D as an electric street railway line. To aid in the understanding of this description, I shall consider railway C as an east and west road with eastbound traffic moving from the left to the right in the drawing, and westbound traffic from the right to the left. The railway D will be spoken of as the north and south road with northbound traffic moving from the bottom to the top in the drawing, and southbound traffic moving from the top to the bottom.

Highway traffic is governed at the intersection of streets A and B by four traffic light signals, one located at each corner and identified by the reference characters H, J, K, and L. Signal H is set to govern traffic moving east on street A, and signal J is set to govern traffic moving west on street A. In a similar manner, signal L governs northbound traffic on street B, and signal K governs southbound traffic. These same signals will be

utilized also, as will later appear, for governing all railway traffic over the crossing. While these signals may take different forms, a preferred form is where each consists of three different colored lights designated by the reference characters G, Y, and R, with an exponent corresponding to the signal. The display of the green light G indicates that traffic may move, the yellow light Y indicates that the direction of traffic is about to be changed, and the display of a red light R requires all traffic to stop. As is the usual practice, the control of these signals is so synchronized that they change colors in step with each other. For example, when signals H and J each display a green light to permit east and westbound traffic to move on street A, the signals K and L each display a red light to stop all traffic on street B. When signals K and L display a green light to permit traffic to move on street B, the signals H and J will each display a red light to stop all traffic on street A. All signals display a yellow light between the changing from the green to red or from the red to green to indicate that the direction of traffic is about to be changed. The significant point in the operation of these traffic signals is that each will display a green light for a predetermined interval of time and then a red light for a predetermined interval of time and the display of green signals on one street takes place at the same time that the red signals are being exhibited on the opposite street. The changing of the signals from one color to the other is in accordance with a prearranged cycle of operation. For railway traffic, the display of a green light is a proceed signal for a train to move over the crossing and the display of a red light is a stop signal.

The controlling element to establish the above cycle of operation for the traffic light signals may be one of many types and is designated in the drawing as a whole by the reference character CR. The time element device CR includes a motor 10 that drives through a proper train of gears, not shown, a shaft indicated by the dotted line 11. Rigidly mounted on shaft 11 are three circuit controlling drums or cams 12, 13 and 14. The drum 12 is provided with a raised portion 15 adapted when engaging a contact spring 16 to raise that spring into engagement with a contact 17. When the drum 12 is rotated in a manner to be later described so that the raised portion 15 is moved out of engagement with the contact spring 16, the spring drops away from the contact 17. The drum 13 is provided with two raised portions 18 and 19 each of which is adapted to be brought at times into engagement with a contact spring 20 to raise the spring into engagement with a contact 21, and when the drum 13 is so positioned that both 18 and 19 are out of engagement with contact spring 20, that spring drops

away from the contact 21. In a like manner, the drum 14 is provided with a raised portion 22 adapted, when brought into engagement with a contact spring 23, to raise the spring into engagement with a contact 24. The raised portions 15, 18, 19, and 22 are so positioned with respect to each other on their respective drums 12, 13, and 14 that starting from the position shown in the drawing the raised portion 15 occupies the first 10° of the circumference taken in a counter-clockwise direction, the raised portion 18 the next 60°, the raised portion 22 the next 120°, and the raised portion 19 the last 60° of the circumference of the drums. It follows that in rotating the drums from the position shown in the drawing in a clockwise direction, as indicated by arrows, the contact 16—17 will be closed and contacts 20—21 and 23—24 opened during the first 120° movement. During the next 60° of a rotation, contact 20—21 will be closed, and contacts 16—17 and 23—24 opened. During the next 120° of a rotation, contact 23—24 will be closed, and contacts 16—17 and 20—21 opened. During the last 60° of a rotation, contact 20—21 will be again closed and contacts 16—17 and 23—24 held open. With the motor 10 rotating the drums 12, 13, and 14 at a uniform speed the above cycle of operation for the contacts 16—17, 20—21, and 23—24 will be repeated over and over again with a definite period of time during which each contact is closed.

The contact 16—17 is included in an operating circuit extending from the BX terminal of a convenient source of current such as a common 110 volt alternating current light circuit, along wire 25, contact 16—17, wire 26, and thence to the signal lights G^K, G^L, R^H, and R^J in parallel and to the opposite terminal CX of the 110 volt source. In order to simplify the drawing as much as possible that it may be more easily understood, these light circuits are not individually shown on the drawing, but indicated by reference characters only. The contact 20—21 is included in an operating circuit that extends from the BX terminal of the current source to the Y lights of each of the signals as will be readily understood by an inspection of the drawing. The contact 23—24 controls an operating circuit from the terminal BX to the wire 27 from which point it branches to the signals G^H, G^I, R^K, and R^L in parallel, and thence to the opposite terminal CX. It follows that, starting from the time the drums 12, 13, and 14 occupy the positions shown in the drawing and during the first 120° of a rotation, the green lights G of signals K and L are illuminated to permit traffic on street B, and the red lights R of signals H and J are illuminated to stop traffic on street A. During the next 60° of a rotation, the yellow lights Y of each signal are illuminated to indicate to all traffic that the direction of traffic is about to be changed. During the next 120° of a rotation, the green lights G of signals H and J and the red lights R of signals K and L are displayed to permit traffic to move on street A and to stop traffic on street B. During the last 60° of a rotation, the yellow lights are again displayed. This operating cycle in the control of the traffic light signals will be repeated each revolution of the drums 12, 13, and 14, as long as the motor 10 is energized to rotate the shaft 11.

The railway C is arranged into two track sections 1—2 and 3—4 by the usual insulated rail joints 5. Each track section is provided with a track circuit including a source of current such, for example, as the secondary 6 of a common track

transformer T and one winding of an interlocking relay TR. As shown in the drawing, the winding 7 of the interlocking relay TR is connected to the track section 1—2 and its winding 8 to the track section 3—4. As is common practice, the armatures 30 and 31 controlled by the windings 7 and 8, respectively, are so interlocked by the interlocking feature, not shown, of the relay TR that when either armature is dropped full-down into engagement with its back contact, it prevents the remaining armature from dropping far enough to engage its back contact even though the associated winding becomes deenergized. The interlocking mechanism, when thus operated, further prevents the said remaining armature from engaging its back contact while the winding which controls the remaining armature continues deenergized, even if the first armature picks up. Relay TR may be of any of a number of forms of this well known type, one of which is shown and described in Patent No. 799,452, entitled "Relay", issued September 12, 1905, to W. W. Coleman.

Associated with the interlocking relay TR is a relay 28 that is energized by virtue of a circuit that can be traced from the BX terminal through wire 25, contact 23—24, wires 27 and 29, winding of relay 28, either back contact of armature 30 operated by the winding 7 of relay TR or the back contact of armature 31 operated by the winding 8 of the relay TR, and thence to the CX terminal of the current source. Normally both windings 7 and 8 of the interlocking relay TR are energized, and the circuit to the relay 28 held open even though the contact 23—24 is intermittently closed by the operation of the time element device CR. An eastbound train entering track section 1—2 will shunt winding 7 to drop armature 30 into engagement with its back contact and thus when the contact 23—24 is next closed, the relay 28 will become energized. As this eastbound train proceeds towards the crossing and then enters the section 3—4, the shunting of the winding 8 of the interlocking relay TR will not cause armature 31 to drop into engagement with its back contact due to the fact that it is prevented from doing so by the armature 30 occupying its full-down position. Thus, as soon as the eastbound train vacates the section 1—2 and winding 7 is again energized, armature 30 is picked up and relay 28 becomes deenergized. A westbound train entering section 3—4 and shunting the winding 8 of relay TR will cause armature 31 to drop to its full-down position as armature 30 is now up and thus the relay 28 is energized the next time that the contact 23—24 is closed in the operation of the time element device CR. As this westbound train enters section 1—2 and shunts the winding 7, armature 30 is prevented from dropping far enough to engage its back contact with the result that relay 28 becomes deenergized as soon as the westbound train vacates the section 3—4. That is, a train on road C approaching the crossing from either direction will cause the relay 28 to become energized, but as a train recedes from the crossing in either direction, the relay 28 becomes deenergized as soon as the train has cleared the crossing. The directional control exerted by the relay TR will appear when the operation of the apparatus is described.

On the electric street railway D, the directional control is established by means of two trolley contactors 32 and 33. These trolley contactors may be any one of many types, several of which are well known to the art. In the form here illus-

trated, the contact plates 35 and 41 of the trolley contactor 32 are located close to but insulated from the trolley wire 34. As the trolley wheel of a car passes the contactor 32, it will engage first one plate and then the other depending upon the direction in which the car is moving. In a like manner, the trolley wheel of a car will engage the contact plates 43 and 48 of the contactor 33. As a northbound car approaches the crossing, its trolley wheel will first make contact between the trolley wire 34 and the contact plate 35, and current will flow from the trolley wire 34 through the trolley wheel and plate 35, and thence along wire 36, back contact of armature 37 of a relay 38, winding of relay 39, and to the ground connection 40 to energize relay 39, it being understood that the trolley wire 34 is connected to one terminal of a generator, not shown, whose other terminal is connected to ground in the usual manner. As the trolley wheel leaves the contact plate 35 and engages the contact plate 41, current is supplied to the relay 39 by the circuit that includes the front contact of its own armature 42 to hold that relay energized until the northbound car has advanced far enough that the trolley wheel moves away from the contact plate 41 at which time the relay 39 becomes deenergized. The trolley wheel of a southbound car moving away from the crossing will first make contact with the contact plate 41 of contactor 32 so that current flows from the trolley wire 34 through the wheel and plate 41, back contact of armature 42 of relay 39, winding of relay 38, and to the ground connection 40 to energize relay 38. Relay 38 is then held energized while the trolley wheel engages the plate 35 by the circuit that includes the front contact of armature 37 as will be readily understood by an inspection of the drawing.

A southbound car approaching the crossing will have its trolley wheel first engage the contact plate 43 of contactor 33 with the result that current is supplied from the trolley wire 34 through the plate 43 and the back contact of armature 44 of a relay 45 to the winding of a relay 46 and thence to a ground connection 47 to energize the relay 46. As the trolley wheel engages the contact plate 48, relay 46 is retained energized through the front contact of its own armature 49. When a northbound car travels away from the crossing, its trolley wheel will first engage the contact plate 48 of contactor 33, and the relay 45 becomes energized by current flowing from the trolley wire 34 and the plate 48 through the back contact of the armature 49 of relay 46, winding of the relay 45, and to the ground connection 47. Relay 45 is then held energized while the trolley wheel engages the contact plate 43 by the circuit that includes the front contact of its own armature 44. It follows that for a southbound car, the relay 46 associated with the trolley contactor 33 is energized as the car approaches the crossing, and the relay 38 associated with the trolley contactor 32 is energized as the car travels away from the crossing. For a northbound car, the relay 39 is energized as the car passes the contactor 32 in approaching the crossing, and the relay 45 is energized as the car passes contactor 33 in travelling away from the crossing. While trolley contactors have been used in connection with traffic on road D to determine the direction of travel, it will be understood that I do not wish to limit myself to trolley contactors but that track circuits and an interlocking relay such as described in connec-

tion with road C could equally as well be used. As a matter of fact, my invention is not limited to any specific manner of determining the direction of traffic, and any standard method may be employed, several of which are well known.

Associated with the directional relays 38, 39, 45, and 46 is a stick relay 50. The relay 50 is normally retained energized by a stick circuit that extends from the positive terminal B1 of a convenient source of current, not shown, back contact of armature 51 of relay 46, wire 52, back contact of armature 53 of relay 39, front contact of its own armature 54, resistance 68, winding of relay 50, and to the negative terminal C1 of the same source of current. Relay 50 can be picked up by either of two circuits, one of which is from the terminal B1 through front contact of armature 55 of relay 45, wire 56, resistance 68, winding of relay 50, and to the negative terminal C1. The second pickup circuit is from terminal B1 through front contact of armature 57 of relay 38, and thence as before traced. It is clear, therefore, that relay 50 will become deenergized whenever a northbound car approaches the crossing and causes relay 39 to be picked up opening the back contact of armature 53 in the stick circuit for relay 50, or when a southbound car approaches the crossing causes the relay 46 to be picked up opening the back contact of armature 51 in the stick circuit for relay 50. As a northbound car travels away from the crossing and causes relay 45 to be picked up to close the front contact of armature 55 or when a southbound car travels away from the crossing and causes the relay 38 to be picked up to close the front contact of armature 57, the relay 50 will be reenergized. That is to say, by means of the trolley contactors 32 and 33 and the associated directional relays, a car on road D approaching the crossing will deenergize the stick relay 50 and the relay will stay down until the car has passed over the crossing and is travelling away from the crossing at which time the relay 50 will be reenergized. The relay 50 controls, in turn, a relay 58 that is provided with an energizing circuit from the terminal BX through wire 25, contact 16-17, wires 26 and 59, winding of relay 58, wire 60, back contact of armature 61 of relay 50, and to the terminal CX.

The operating circuit for the motor 10 of the time element device CR is controlled jointly by the relays 28 and 58. This operating circuit can be traced from the terminal B1 through the back contacts of armatures 62 and 63 of relay 58 in parallel, wire 64, back contacts of armatures 65 and 66 of relay 28 in parallel, wire 67, motor 16, and to the terminal C1. It follows that as long as both relays 28 and 58 remain deenergized, the motor 10 is active to operate the drums 12, 13 and 14 in the manner previously pointed out, but with either relay 28 or 58 picked up, the motor 10 is deenergized and the drums 12, 13, and 14 of device CR are stopped and remain stationary.

In describing the operation of the apparatus of my invention, I shall first assume that there is no train approaching on either road C or D. With road C free from traffic, the interlocking relay TR is picked up holding the circuit to relay 28 open and that relay is deenergized. With no traffic on road D within the limits of the trolley contactors 32 and 33, the relay 50 is held energized and the relay 58 is deenergized by its circuit being held open at the back contact of armature 61 of relay 50. As pointed out above, with both relays 28 and 58 deenergized, the operating

circuit to the motor 10 is completed and the motor active to rotate the drums 12, 13, and 14 at a uniform rate resulting in the control of signals H, J, K, and L in such a manner that highway traffic is permitted to proceed first on street A and then on street B.

Assuming now that an eastbound train enters the track section 1-2 and shunts the winding 7 of relay TR to drop armature 30 into engagement with its back contact: The next time drum 14 is operated around to where it closes the contact 23-24, the relay 28 becomes energized and picking up its armatures 65 and 66 opens the operating circuit to the motor 10. The operation of the device CR is now stopped with the drums 12, 13, and 14 so positioned that the contact 23-24 is closed and the contacts 20-21 and 16-17 are both open. Contact 23-24 being held closed, the circuits to the green light G of signals H and J and to the red lights of signals K and L are closed, and these signals are continually displayed.

The display of the green light of the signal H permits the eastbound train to advance towards the crossing, and the display of the red lights of signals K and L acts to stop not only the highway traffic on street B but to stop any car approaching the intersection on the railway D. As the eastbound train proceeds over the crossing and enters the track section 3-4, winding 8 of the interlocking relay TR is shunted but its armature 31 is prevented from dropping into contact with its back contact by the interlocking feature of this relay. The vacating of the section 1-2 by the eastbound train, permits winding 7 to become re-energized, and the relay 28, in turn, deenergized, with the result that the motor 10 is again started into operation and the normal operation of the traffic signals H, J, K, and L resumed.

A westbound train approaching the crossing will shunt winding 8 causing its armature 31 to engage its back contact. With armature 31 full-down, the relay 28 is picked up the next time the contact 23-24 is closed in the normal operation of the device CR. Again the motor 10 is stopped at a position where the contact 23-24 is closed, and the contacts 20-21 and 16-17 are both open. Thus the circuits to the green lights of signals H and J and to the red lights of signals K and L are continuously held closed, and the westbound train permitted to advance towards the crossing while all north and southbound traffic is stopped. Armature 31 being in its full-down position, the armature 30 is prevented from dropping into engagement with its back contact as the westbound train enters the section 1-2 and shunts the winding 7 of relay TR. Relay 28 is thus deenergized as soon as the section 3-4 is vacated by the westbound train and the winding 8 of relay TR reenergized. The deenergizing of relay 28 closes the circuit to motor 10 and the normal operation of the signals is resumed under the control of the time element device CR.

A northbound car passing the trolley contactor 32 will operate the relay 39 in the manner pointed out above to open the stick circuit of relay 50 to deenergize that relay. The next time drum 12 is rotated around to where it closes the contact 16-17, the relay 58 is picked up to open the motor circuit at the back contacts of its armatures 62 and 63. The device CR being stopped at a point where the contact 16-17 is held closed, the signals K and L each display a green light, and the signals H and J a red light. Traffic being thus established for the road D, the northbound car

can advance over the crossing while all east and westbound traffic both highway and railway are stopped. The northbound car on passing the trolley contactor 33 as it moves away from the crossing operates the relay 45 to close the pickup circuit for relay 50, and that relay is reenergized. As soon as the relay 50 is picked up, relay 58 becomes deenergized and the normal operation of the device CR re-established.

A southbound car approaching the crossing will operate the relay 46 as it passes the trolley contactor 33 to open the stick circuit for relay 50 with the result that the relay 58 is energized the next time the contact 16-17 is closed in the normal operation of the time element device CR. Again signals K and L each display a green light, and the signals H and J a red light. The southbound car passing the trolley contactor 32 as it moves away from the crossing, operates relay 38 to reenergize relay 50 and, in turn, deenergize relay 58 to re-establish the normal operation of the device C. It is to be noted that after a car or train enters upon the approach limits, the traffic signal will be held in the clear position for that particular car or train from the time that the clear signal is automatically displayed by the normal operation of the time element device until after the car or train has passed over the crossing. In other words, after the signal has been fixed in the clear position, as the result of a train or car entering within the approach control, the time element device is rendered inactive until after the car or train has advanced over the intersection. The principle being that the train or car will automatically retain the green light for the signal governing traffic in the direction of its travel and the red light for the signals governing all intersecting traffic, the control being gained only after the signal has appeared green in the usual operation. In this manner, no short-timing of any signal is ever effected.

Let us now assume the case where, after an eastbound train has entered the section 1-2 and relay 28 has picked up and the device CR is at a position to cause the signals H and J to be green and the signals K and L to be red, a southbound car passes the trolley contactor 33 causing the relay 50 to become deenergized. As the device CR is now held stationary with contact 23-24 closed and contact 16-17 open, the signals H and J remain green, and the signals K and L red, thereby permitting the eastbound train to advance over the crossing but stopping the southbound car even though it has acted to select the direction of traffic. As soon as the eastbound train vacates the section 1-2 and clears the crossing, the relay 28 is deenergized and the motor 10 started. The time element device CR will be operated around to the point where the contact 16-17 is closed at which time the relay 58 will be picked up as the relay 50 is now down having been deenergized as the southbound car passed the trolley contactor 33. Device CR being this time stopped where contact 16-17 is held closed, the signals K and L display a green light, and the signals H and J a red light. Thus the southbound car can advance over the intersection immediately after the eastbound train has passed. As the southbound car passes the contactor 32, the normal operation of the device CR is re-established in the manner previously described.

The operation of the apparatus for traffic in other directions will be similar to that already pointed out, and it is thought that it needs no further description.

The apparatus here disclosed provides simple and reliable means for controlling a set of signals adapted to govern traffic through the intersection of two traffic routes on which two different classes of traffic travel. The signals are normally operated in a manner to accommodate a second class of traffic which, in this instance, is highway traffic by alternately setting the signals first for one route and then for the other route. Traffic of the first class of traffic which, in this instance, is railway traffic, is given preference in that the normal operation of the signals is stopped and the route set to permit the advancing of traffic on the route in which the traffic of the first class is approaching the intersection. The approach of traffic of the first class on both routes results in the signals being cleared for the route on which the first class traffic has first entered the approach limits. As soon as the traffic on this first route has cleared the intersection, the signals are automatically changed and preference is given to the first class traffic on the other route.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a stretch of railway track intersected by a traffic route, railway signals for governing traffic movements on said railway track across said traffic route, traffic signals for governing traffic movements on said traffic route across said railway track, a timing device, means for normally energizing said timing device, means controlled by said timing device for clearing said traffic signals alternately with said railway signals while said timing device is energized, and means controlled by a train on said railway track for deenergizing said timing device for retaining said railway signals in the clear condition when said train is approaching said traffic route from either direction and for causing said timing device to become energized when said train crosses said traffic route and also for preventing means controlled by said train from deenergizing said timing device while said train is receding from said traffic route.

2. In combination, a stretch of railway track intersected by a traffic route, railway signals for governing traffic movements on said railway track across said traffic route, traffic signals for governing traffic movements on said traffic route across said railway track, a timing device, means for normally energizing said timing device, means controlled by said timing device for clearing said traffic signals alternately with said railway signals while said timing device is energized, and means controlled by a train on said railway track for deenergizing said timing device for retaining said railway signals in the clear condition when said train approaches within a given distance in either direction from said traffic route and for causing said timing device to become energized when said train crosses said traffic route and also for preventing means controlled by said train from deenergizing said timing device when said train recedes to said given distance from said traffic route.

3. In combination, a stretch of railway track comprising a first track section and a second track section one end of which is adjacent a given

end of said first track section, a traffic route intersecting said railway track near the adjacent ends of said first and second track sections, an interlocking relay comprising a first and a second control winding, a track circuit for said first track section including the rails of said first track section and said first control winding as well as a source of current, a track circuit for said second track section including the rails of said second track section and said second control winding as well as a source of current, a timing device, means for normally energizing said timing device, railway signals for governing traffic movements on said railway track across said traffic route, traffic signals for governing traffic movements on said traffic route across said railway track, means controlled by said timing device for clearing said traffic signals alternately with said railway signals while said timing device is energized, and means controlled by said interlocking relay for deenergizing said timing device for retaining said railway signals in the clear condition while a train in either of said track sections is approaching said traffic route and for energizing said timing device while a train is receding from said traffic route.

4. In combination, a stretch of railway track intersected by a traffic route, a timing device, means for normally energizing said timing device, railway signals for governing traffic movements on said railway track across said traffic route, traffic signals for governing traffic movements on said traffic route across said railway track, means controlled by said timing device for clearing said traffic signals alternately with said railway signals while said timing device is energized, and means controlled by said timing device and by a train on said railway track for deenergizing said timing device for retaining said railway signals in the clear condition when said train is approaching said traffic route from either direction and for afterwards energizing said timing device and preventing its subsequent deenergization by said train while said train is receding from said traffic route in either direction.

5. In combination, a stretch of railway track intersected by a traffic route, a timing device, means for normally energizing said timing device, railway signals for governing traffic movements on said railway track across said traffic route, traffic signals for governing traffic movements on said traffic route across said railway track, means controlled by said timing device for clearing said traffic signals alternately with said railway signals while said timing device is energized, a pair of train controlled directional relays one of which becomes energized only when a train in a given direction from said traffic route is approaching said traffic route and the second of which becomes energized only when a train in said given direction from said traffic route is receding from said traffic route, a second pair of train controlled directional relays one of which becomes energized only when a train in the opposite direction from said traffic route is approaching said traffic route and the second of which becomes energized only when a train in said opposite direction from said traffic route is receding from said traffic route, means controlled by the first relay of each of said pairs for deenergizing said timing device, and means controlled by the second relay of each of said pairs for energizing said timing device.
